CLAIM

The ornamental design for a strut suspension spacer, as shown and described.

DESCRIPTION

FIG. 1 is a front top perspective view of the strut suspension spacer of the present invention;

FIG. 2 is a rear, bottom perspective view of the spacer shown in FIG. 1;

FIG. 3 is a front view of the spacer shown in FIG. 1;

FIG. 4 is a back view of the spacer shown in FIG. 1;

FIG. 5 is a left end view of the spacer shown in FIG. 1; and,

FIG. 6 is a right end view of the spacer shown in FIG. 1.

The broken lines showing voids and contours are for illustrative purposes only, and forms no part of the claimed design.

1 Claim, 2 Drawing Sheets
